UNITED STATES PATENT OFFICE.

FRANK L. SESSIONS, OF COLUMBUS, OHIO, ASSIGNOR TO THE JEFFREY MANUFACTURING COMPANY, A CORPORATION OF OHIO.

LOCOMOTIVE.

Specification of Letters Patent. Patented Mar. 23, 1915.

1,132,799.

Application filed March 7, 1910. Serial No. 547,837.

To all whom it may concern:

Be it known that I, FRANK L. SESSIONS, a citizen of the United States, residing at Columbus, in the county of Franklin and 5 State of Ohio, have invented certain new and useful Improvements in Locomotives, of which the following is a specification, reference being had therein to the accompanying drawing.

10 This invention relates to improvements in electric locomotives and more especially to the journal boxes for the axles and the means for adjusting them.

One of the objects of my invention is to 15 provide, in an electric locomotive having connecting rods, means for adjusting the distance between the axles in conformity with the length of the rods.

Further objects are to provide certain improved details of journal box construction 20 and mounting.

In the accompanying drawings—Figure 1 is a side view of an electric locomotive provided with journal boxes and adjusting 25 means embodying the invention. Fig. 2 is a side elevation of one of the boxes and connected parts on a larger scale. Fig. 3 is a vertical sectional view on line 3—3, Fig. 2. Fig. 4 is a horizontal section on line 4—4, Fig. 3. Fig. 5 is a side view of the pedestal. Fig. 6 is a plan view of the same. Fig. 7 is a top plan view of the brace and dowels. Fig. 8 is a side view of the same. Fig. 9 is an elevation of the gib. Fig. 10 is a central vertical section of the same.

35 Referring to the drawings, A represents as a whole the frame of the locomotive. This frame is preferably constructed of rolled steel sections. As shown in the drawings, the frame consists of end parts 1, 1, each comprising a single channel section, and side parts 2, each comprising a lower channel section 2^a secured to the end channel sections and an upper channel section 2^b secured to the lower channel section 2^a. Each 40 of the lower channel sections 2^a is made up of three parts each being separated to provide openings 2^c for the journal boxes and associated parts to be described.

45 50 3, 3 represent the main axles and 3^a, 3^a represent the locomotive supporting wheels secured to the ends of the axles 3^b, 3^b between which there extends a connecting rod 3^c. The journal boxes for the axles 3 are 55 each composed of upper and lower separable parts 4 and 5.

6 represents the main bearing portion of the box and is suitably babbitted. It engages with the journal part of the axle and lies within a suitable aperture in the main 60 part 4 of the box.

At 7 are indicated lubricating ducts in the part 4 for the main bearing 6.

The lower flange of the upper channel section 2^a extends above the journal box 65 opening 2^c. Between this flange and the box are interposed springs 9 through which the weight of the frame is transmitted to the box, axle and wheels. The springs are fitted at their lower ends in recesses 10 in the box 70 and at their upper ends fit over bosses 11 bolted to the under side of the flange 8. At its sides the box is formed with vertical straight channels 12.

13 is a guide frame for the journal box 75 comprising a U-shaped plate 14 which fits against the outer face of the frame 1 around the opening 2^c and is riveted to the frame as indicated at 15. The end elements of the frame constitute pedestals for the box, these 80 being connected together by the longitudinal top member. The pedestals are provided with integrally formed guides 16 which extend within the limits of the opening 2^c both laterally inward to points substantially in 85 line with the channels 12 of the box and thence toward the box. These guides are formed with tapered faces 17 which incline upward and outward in the reverse from the ordinary direction. There is also provided a bottom brace 18 which extends across 90 the lower part of the opening 2^c and unites the pedestals with each other. The under faces of the guides 16 of the pedestals are formed with recesses 19 and the top face of 95 the brace with corresponding recesses 20 and in these recesses fit dowels 21 which give a very strong connection between the brace and the guides against the horizontal strains transmitted from the wheels, axle and journal box.

100 22 indicates bolts which pass up through the brace and through the dowels and are screwed into the bottoms of the guides 16.

105 23. Box-engaging adjusting gibs are shown at 23. They are arranged one at each side of the journal box, interposed between the guides 16 and the box, and are formed with inner vertical straight faces which have a sliding fit within the channels 12 of the box. 110 They are also formed on their outer faces toward the guides with channels 24 tapered

- to correspond and have a sliding fit with the tapered faces 17 of the guides. The gibbs are vertically adjusted, to closely confine the journal box but allow of its vertical play, by means of screws 25 which engage threaded holes in the upper ends of the gibbs and which pass up through the flange 8 of the locomotive frame A.
- 26 is a fixed nut on the screw 25, being pinned thereon at a suitable point to bear on the under side of the flange 8.
- 27 is the head of the screw arranged above the flange 8 in an accessible location allowing of the adjustment of the gibbs from time to time with great convenience.
- 28, 29 are jam nuts on the screw above the flange 8 by which the screw is held securely in its adjusted position. 30 is an angle washer interposed between the jam nuts and the said flange and shaped to fit the upper inclined surface of the flange.
- In the operation of adjustment the gibbs are held from turning by their engagement with the guides 16 and may be forced downward to hold the journal box more closely or may be drawn upward to leave it more free, by the action of the screws 25 which engage the gibbs by their threads and are held from vertical movement in the flange 8.
- 30 The openings in the flange 8 through which the screws 25 pass are indicated at 31 and enlarged or elongated to allow the screws to shift as may be required to accommodate the horizontal shifting of the gibbs.
- 35 It will be observed that by my invention I have provided not only means for adjusting the engagement of the slideable journal box with its guides, but also means for regulating within narrow limits the distance between the two axles. When a connecting rod is used, as in the present case, this adjustment is very essential as it is necessary for efficient and proper operation that the distance between the axles be the same as the length of the rod. It will be obvious that either of the boxes may be moved laterally as desired by moving one gib upward and the other downward, or vice versa. This need for horizontal adjustment is especially great in the case of a locomotive having a frame made up of structural steel parts. A separate bearing guiding frame is necessary when a structural steel frame is used and this cannot be riveted or otherwise attached to the frame with sufficient accuracy to secure it at that exact relative location of the machined surfaces which is essential.
- What is claimed is:—
1. In an electric locomotive, the combination of the side frame having a downward directed opening and a horizontal flange above the opening, the pedestals attached to the frame at the opening, the said pedestal extending under the flange and having guides inclined downward and inward to-

ward each other, inclined gibbs engaging the guides, screws engaging the gibbs and the flange and having operating heads above the flange, and a vertically movable journal box engaging the gibbs, substantially as set forth. 70

2. In an electric locomotive the combination of the side frame having a downward directed opening with vertical edges, the guide frame having a vertical flange attached to the outer face of the frame at the opening, and also downward and inward inclined guides extending within the opening, vertically adjustable gibbs fitting the guides, and a journal box engaging the gibbs, substantially as set forth. 75

3. In an electric locomotive, the combination of the side frame having a downward directed opening, a guide frame comprising pedestals and extending partly around the opening and attached to the frame and extending within the opening where it is provided with guides, a brace, dowels inserted in the brace and in the lower ends of the pedestals, bolts passing through the brace and dowels and into the pedestal, vertically adjustable gibbs engaging the guides, and a journal box engaging the gibbs, substantially as set forth. 80

4. In a locomotive, the combination of the main frame consisting of structural steel parts having integrally connected pedestals fastened to the frame, journal boxes positioned between the pedestals and movable longitudinally of the locomotive, two separate wedge-shaped box-engaging adjusting devices for each box movable independently of each other along lines crossing the horizontal plane of the box axis, means for positively moving either of the said adjusting devices independently of the other in either direction and for independently locking each adjusting device after vertical adjustment whereby the box can be positively moved horizontally forward or backward upon opposite vertical movements of the adjusting devices and positively locked in adjusted position, axles in the said journal boxes, crank pins connected with the axles, and connecting rods between the crank pins of adjacent axles. 95

5. In a locomotive, the combination of a frame, having each side made up of superposed rolled steel sections, the lower of which is interrupted to provide spaced openings, bearing pedestals independent of the frame but secured thereto at the said openings, bearing boxes connected with the said pedestals for vertical movement, means for adjusting the boxes horizontally relative to the pedestals, axles upon which the boxes are mounted, supporting wheels for the axles, crank pins on the wheels, and connecting rods between the crank pins of adjacent wheels, substantially as set forth. 100

6. In a locomotive, the combination of a 105

frame, each side of which comprises a structural steel section, bearing pedestals secured to the frame below the said structural steel sections on each side of the locomotive, bearing boxes mounted in the said pedestals for relative vertical movement, resilient means above the tops of the bearing boxes and engaging the bottoms of the said structural steel sections independently of the pedestals, axles supporting the bearing boxes, and track wheels on the axles, substantially as set forth.

7. In a locomotive, the combination of a frame, each side of which comprises a structural steel section having an inward extending flange at its lower edge, bearing pedestals secured to the frame at each side below the said structural steel sections, the said pedestals having opposite guides inclined downward and inward toward each other, vertically adjustable gibs engaging the guides and having correspondingly inclined faces, vertically movable journal boxes engaged and guided by the said gibs, means interposed between the gibs and the said lower flanges of the structural steel sections for adjusting the gibs, axles for the journal boxes, and track wheels on the axles, substantially as set forth.

8. In a locomotive, the combination of a frame having sides made up of superposed structural steel sections, the upper one of which is provided at its lower edge with an inward extending flange and the lower one of which is interrupted to provide spaced openings, bearing pedestals independent of the frame but secured thereto at the said openings, the said pedestals having opposite downward and inward inclined guides, correspondingly inclined gibs adapted to slidably engage the guides and vertically slidably engage the journal boxes engaged and guided by the gibs, resilient devices interposed between the tops of the boxes and the said lower flanges of the upper rolled steel sections, gib adjusting means interposed between the gibs and the said flanges, axles upon which

the journal boxes are mounted, bearing wheels at the ends of the axles, crank pins on the wheels, and connecting rods between the crank pins of adjacent wheels, substantially as set forth.

9. In a locomotive, the combination of a frame, each side of which comprises a structural steel section having an inward extending flange at its lower edge, bearing pedestals secured to the frame at each side below the said structural steel section, said pedestals having, an inclined guide at one side, gibs adapted to engage the said guides and having correspondingly inclined surfaces, vertically movable journal boxes each adapted to be engaged at one side and guided by one of the said gibs, means interposed between the gibs and the said lower flanges of the structural steel sections for vertically adjusting the gibs, axles for the journal boxes, and track wheels on the axles, substantially as set forth.

10. In a locomotive, the combination of a frame, each side of which comprises a structural steel section, bearing pedestals secured to the frame below the said structural steel sections and having opposite downward and inward inclined guides, correspondingly inclined gibs adapted to slidably engage the guides, vertically slidable journal boxes engaged and guided by the gibs, resilient locomotive supporting means interposed between the tops of the boxes and the lower flanges of the said structural steel sections, gib adjusting means interposed between the gibs and the said flanges, axles in the journal boxes, track wheels at the ends of the axles, crank pins on the wheels, and connecting rods between the crank pins of adjacent wheels, substantially as set forth.

In testimony whereof I affix my signature, in presence of two witnesses.
